UNITED STATES PATENT OFFICE.

EDWARD LAPARLE, OF OAKLAND, CALIFORNIA.

VALVE-TRUING TOOL.

Application filed August 27, 1919. Serial No. 320,235.

To all whom it may concern:

Be it known that I, EDWARD LAPARLE, a citizen of the United States, and a resident of Oakland, county of Alameda, and State of California, have invented a new and useful Valve-Truing Tool, of which the following is a specification.

My invention relates to portable devices for truing or dressing the faces of valves especially the poppet valves of internal combustion engines.

An object of the invention is to provide a truing tool which will insure accurate results notwithstanding the characteristic deformation of the valve stem due to wear.

Another object of the invention is to provide a device such as will enable the valve to be quickly and securely placed in position for the truing operation.

The invention possesses other objects and features of advantage, some of which, with the foregoing, will be set forth in the following description of the preferred form of my invention which is illustrated in the drawings accompanying and forming a part of the specification. It is to be understood that I do not limit myself to the showing made by the said drawings and description, as I may adopt variations of the preferred form within the scope of my invention as set forth in the claim.

Referring to said drawings:

Fig. 1 is a plan view of the truing tool, the valve being shown positioned therein.

Fig. 2 is a vertical section of the device, the plane of the section being indicated by the line 2-2 of Fig. 3.

Fig. 3 is a vertical section taken on the line 3-3 of Fig. 2.

Frequently the poppet valves of an internal combustion engine become warped or misshapened so that they do not seat properly. The valve face must then be trimmed until the original circumference and taper obtain once more. During this trimming operation the valve is usually supported by mounting the valve stem for rotation in a pair of aligned clamps. It is imperative that these clamps should so hold the stem that the valve will rotate in affixed cooperative relation with the cutting blade of the truing tool and thereby become accurately trimmed. Since the clamps are generally two in number they will therefore engage the stem at two spaced points intermediate its ends. If the valve stem is

of the same diameter throughout its length then the clamps will hold the valve properly. However the stem invariably becomes much thinner at that portion which is continually pressing against the sides of its bearing when the engine is operating, due to the pressure of the intake or exhaust gases. Since the length of the stems for the different engines vary considerably, it is almost invariably the case that unless labor entailing adjustments are made, one of the tool clamps will engage a thin section of the stem and the other a thick section, thereby throwing the valve completely out of alignment and making it impossible to trim the valve with any degree of accuracy.

In accordance with my invention the valve stem automatically assumes a correct position and therefore insures an accurate cutting of the valve.

A detailed description of my invention follows:

The apparatus comprises a pair of jaws 2 and 3 between which the stem 4 of the valve 5 is arranged to be positioned. The jaws are pivoted together at one edge, the eyes 6 and 7 and pin 8 disposed on the inner side of the jaws being partly provided for that purpose. The jaw 2 is preferably formed with an integral supporting member 9 which may be set in a vise to anchor the tool if desirable.

Means are provided as hereinbefore mentioned, for insuring the correct positioning of the valve stem. Formed on the inner sides of the jaws and preferably integral with the eyes 6 and 7 are a plurality of spaced longitudinally aligned teeth 10 and 12. The teeth 10 of the jaw 2 are arranged to fit in the spaces 13 between the teeth 12 of the jaw 3 and vice versa the teeth 12 are arranged to engage the spaces 14 of the jaw 2. By referring to Figure 2 it will be clearly seen that when a valve stem having a worn portion such as at 15, is inserted between the jaws, at least one tooth of each jaw will engage the undeformed portion of the stem at both the forward and rear end of the jaws, thereby insuring the proper truing of the valve.

The teeth are each provided with a V-shaped recess 16 thereby providing a four point contact between each pair of teeth that are in contact with the stem. This construction has several advantages over a three point contact, since a better bearing

is provided within which the stem may rotate and a much smaller error in alignment of the valve will prevail in case an insufficient number of teeth engage the valve stem.

- 5 Simple means are provided for normally maintaining the jaws in an extended position and for drawing said jaws together when it is desired to grip the valve. Encircling the pin 8 and interposed between 10 the jaws is a spring 17 which presses against the inner sides of the jaws and thereby tends to keep the jaws extended. Engaging the free edges of the jaws 2 and 3 is a screw threaded bolt 18 formed with a rectangular neck 19 which loosely engages a correspondingly shaped aperture 19^a provided in the jaw 2. The threaded end of the bolt extends thru an enlarged aperture 20 formed in the jaw 3. A winged nut 21 engages the bolt on the outer side of the jaw 3 while the head 22 of the bolt bears against the outer side of the jaw 2. With this construction the jaws may be opened or closed by simply turning a single nut, thereby saving considerable time dispensing with a number of loose parts.

The jaw 2 is provided at one end with a cutting blade 23 which has its cutting edge 24 disposed in the path of the valve face 25. 30 The opposite end of the jaw 2 is provided with an adjustable screw 26 which is arranged to engage the free end of the valve stem to limit the amount that the valve may be trimmed.

35 In operation of the device the valve stem

is inserted in the recesses 16 and the winged nut 21 rotated until the stem is properly gripped. The screw 26 is then adjusted so that the face of the valve properly contacts with the cutting blade. To rotate the valve 40 it is convenient to use an ordinary brace (not shown) provided with a key 27 that can be inserted in the recesses 28 provided in the valve.

I claim:

45 A valve truing tool, comprising a pair of jaws pivotally connected adjacent one edge and arranged to be longitudinally disposed along the valve stem, a plurality of longitudinally spaced teeth on the inner side 50 of each jaw arranged to cooperatively engage only full-sized portions of said stem throughout its length, the teeth of each jaw being arranged to engage in the spaces between the teeth of the other jaw, a cutting member adjustably secured to one end of one of said jaws and having its cutting portion positioned to lie in the path of the valve face when the valve is operatively held in the tool, means resiliently urging said jaws 55 apart a single means for holding said jaws together to retain the teeth in engagement with said stem and means provided on the jaw carrying said cutting member for limiting the movement of the valve against said cutting member.

55 In testimony whereof, I have hereunto set my hand at Oakland, California, this 16th day of August 1919.

EDWARD LAPARLE.
